J. R. SANDBERG,

COMBINED SASH OR DOOR LOCK AND BURGLAR ALARM.

APPLICATION FILED MAY 1, 1920.

1,358,249.

Patented Nov. 9, 1920.

UNITED STATES PATENT OFFICE.

JOHN R. SANDBERG, OF DENVER, COLORADO.

COMBINED SASH OR DOOR LOCK AND BURGLAR-ALARM.

1,358,249.

Specification of Letters Patent. Patented Nov. 9, 1920.

Application filed May 1, 1920. Serial No. 378,173.

To all whom it may concern:

Be it known that I, JOHN R. SANDBERG, a citizen of the United States of America, residing at the city and county of Denver 5 and State of Colorado, have invented a new and useful Combined Sash or Door Lock and Burglar-Alarm, of which the following is a specification.

This invention relates to improvements in 10 combined sash or door locks and burglar alarms.

The object of the invention is to provide a device of this character, which is primarily adapted for locking a window sash 15 at any desired point in its upward movement, said locking device being electrically connected in circuit with a bell in such manner that any attempt to move the window in either direction results in closing a circuit through the bell, which is thereby rung.

Further, to provide a sash lock comprising a fixed member which is secured to the lower sash, having a movable member, which is slidably connected to a rod secured 25 on the upper sash and adapted to be locked thereto, said fixed and movable members being electrically connected in circuit with a bell, whereby a slight movement of the window in either direction causes contact between the fixed and movable members, by 30 which a circuit is closed through the bell.

These objects are accomplished by the device illustrated in the accompanying drawings, in which:

35 Figure 1 is a vertical, sectional view through the upper and lower sashes of a window, showing the application of the improved locking device thereto.

Fig. 2 is a front view—full size—showing 40 the locking member which is secured to the upper rail of the lower sash, and a portion of the rod to which the locking member is adapted to be locked, and which is secured at one end to the upper sash.

45 Fig. 3 is a front view of the locking member, the cover plate being removed to show the inclosed mechanism.

Fig. 4 is a transverse, sectional view on the line 4—4 of Fig. 2.

50 Fig. 5 is a front view, partly in section, of the lock member casing, showing the manner of insulating therefrom, a contact which is secured to the side of said casing, and

55 Fig. 6 is a side view of the slide block which is mounted in the casing, and which

is adapted to be locked to the rod on the upper sash, which passes through said block.

Referring to the accompanying drawings: 60

The numeral 1 designates the upper sash of a window, and 2, the lower sash thereof. To the upper rail 3, of the upper sash, and near one end of the same, is secured a plate 4, having a projecting hub 5, which is provided with a threaded aperture in which is screwed the horizontally bent end portion 6, of a vertically depending rod 7, which extends to a point slightly below the upper rail 8, of the lower sash 2, when the same 70 sash is closed, or at the limit of its downward movement. Upon the upper rail 8, of the lower sash, and in vertical line with the rod 7, is secured a casing or housing 9, having a cover plate 10, which fits snugly 75 within the sides and ends of the housing, and rests upon abutments 11, in the corners of the housing, as shown. Screws 12, pass through holes in the corners of the cover and also through holes 13, in the bottom of 80 the housing, and are screwed into the rail 8, thus rigidly securing the housing to the said rail.

Each end of the housing has a central aperture 14, and in these apertures is 85 mounted a bolt or rod 15, the ends of which project slightly beyond the ends of the housing and are threaded, and nuts 16, are screwed upon the ends of the bolt and against the ends of the housing, and thus 90 rigidly secure the bolt to the ends of the housing.

Upon the bolt 15, is loosely mounted a slide block 17, which is held centrally of the length of the bolt, by expansion coil springs 18, which surround the bolt, and are held under tension between the ends of the block and the ends of the housing, as clearly shown in Fig. 3. The springs exert equal pressure on each side of the block, and the block is thereby normally held in a central position on the bolt, as above stated, but may be moved a short distance in either direction, for a purpose to be hereinafter explained. The block projects out through an elongated slot 10^A, 105 in the cover 10. Above the hole 19, in the block through which the bolt 15, passes, is a slightly larger hole 20, which is parallel with the hole 19, and this hole 20, is intersected by a threaded aperture 21, which extends down 110 through a short neck 22, formed on the outer end of the block. The vertical rod 7, passes

- loosely through the hole 20, in the block, which permits the block to slide on the rod, as the lower sash is raised or lowered, and a thumb screw 23, is secured into the aperture 21, which screw, when turned tightly against the rod, holds the sash in any desired position, except for a slight movement in either direction against the tension of one or the other of the springs 18. The device thus far described, provides for simply locking the sash in a closed position, or at any point in its upward movement, independently of any alarm system operated by the movement of the sash, but the invention contemplates the employment of an alarm bell, arranged in an electric circuit with the casing 9, and slide block 17, whereby, when the sash is moved in either direction, a circuit is closed through the bell and an alarm is sounded.
- 20 In carrying out this feature of my invention, I secure upon the inner face of one side of the housing 9, a contact 24, consisting of a metal strip having spaced abutment lugs 25, which are provided with threaded holes. An insulating strip 26, is interposed between the contact 24, and the side of the housing, and insulating rings 27 are inserted in holes in the side of the housing and are formed with flanges which rest against the outside face of the casing, and screws 28 and 29 are passed through the flanged rings 27, and through the strip 26, and screwed into the holes in the contact 24, thus securing the contact to the side of the housing.
- 30 The screw 28, is an ordinary headed screw, but the screw 29, is headless and a jam nut 30, is screwed upon it against the flanged ring 27, as shown in Fig. 5.
- 35 The slide block 17, is provided with a projecting pin 31, which acts as a contact, and normally lies midway between the lugs 25, of the contact 24, and a binding screw 32, enters a hole 33, near the outer end of the block.
- 40 An electrically operating bell 32^A, of the usual construction, is secured at any desired place in the house, though in the drawing, the same is shown, for convenience of illustration, as secured to the window frame.
- 45 A circuit wire 34, is connected at one end to one of the bell terminals, and at its other end it is clamped to the block 17, by the binding screw 32. A circuit wire 35, is connected at one end to the remaining bell terminal, and its other end is connected to one pole 36, of a battery 37. A circuit wire 38, is connected at one end to the other pole 39, of the battery, and at its other end it is clamped between the jam nut 30, and a binding nut 40, on the headless screw 29.
- 50 The lower sash may be locked in a closed position or at any point in its upward movement, and when it is desired to raise the sash, the thumb screw 23, is unscrewed sufficiently to permit the block 17, to slide freely on the rod 7, until the sash is raised to the desired

point, when the said screw is turned to clamp the block tightly to the rod 7.

As the springs 18, normally hold the block 17, on the rod 15, in a position centrally of the length of the housing 9, the contact 31, on said block normally lies midway between the abutments 25, on the contact 24, of the housing, and thus an open circuit is normally maintained through the bell and battery. But if an attempt is made to move the sash either up or down, the block 17, which is clamped to the rod 7, remains stationary, and the movement of the sash, which is against the tension of one or the other of the springs 18, causes one of the abutments 25, of the contact 24, to engage the contact 31, on the block 17, whereby the circuit through the bell and battery is closed and an alarm is sounded.

The bell and locking mechanism may be connected with the house lighting system if desired, but a battery is preferable, as it eliminates the otherwise necessary wiring and permits the instalment of the sash lock at any time, by an unskilled person.

90 The circuit wires 34 and 38, should be of sufficient length to permit the sash to be raised to its full height.

95 By attaching the device on one side of the sash, it is not only out of the way, but is not likely to be seen by a person attempting to open the window from the outside.

100 While the device is shown in connection with a window sash, it may also be adapted for use in connection with doors and with the lids of chests and the like.

Having described my invention, what I claim as new and desire to secure by Letters Patent, is:

1. In a combined sash lock and burglar alarm, the combination with an upper and lower sash, and a depending rod on said upper sash, of a fixed housing on said lower sash having a circuit terminal contact, a block slidably mounted in said housing having a hole through which said depending rod passes, and a circuit terminal contact normally out of engagement with the housing contact, means for locking said block to said rod, whereby movement of the sash causes the contacts to engage and thus close a circuit.

105 2. In a combined sash lock and burglar alarm, the combination with an upper and lower sash, and a depending rod on said upper sash, of a fixed housing on said lower sash, a block slidably mounted in said housing having a hole through which said depending rod passes, and a circuit terminal contact, a thumb screw for locking said block to said rod, a circuit terminal contact on said housing, and means for normally holding said block in a position in which its contact is out of engagement with that of the housing, whereby, when the sash is 110

moved, the contacts are brought into engagement, thus closing the circuit.

3. In a combined sash lock and burglar alarm, the combination with an upper and lower sash, and a depending rod on said upper sash, of a fixed housing on said lower sash, a bolt in said housing, a block slidably mounted on said bolt, having a hole through which said depending rod passes, and a thumb screw in said block for locking the same to said rod, a circuit terminal contact on the housing and insulated therefrom, a circuit terminal contact on the block, and resilient means for normally holding the block in a position where its contact is out of engagement with the housing contact, said contacts being brought into engagement by the movement of the sash, thereby closing an electric circuit.
- 20 4. In a device of the character described, the combination with an upper and lower sash, and a depending rod on said upper

sash, of a fixed housing on the lower sash, a bolt secured in said housing, a block slidably mounted on said bolt having a hole 25 through which said depending rod passes, and a thumb screw in said block for locking the same to said rod, expansion coil springs on said bolt and interposed between the ends of the block and the ends of the housing 30 for centering said block on said belt, a circuit terminal contact on the housing and insulated therefrom, having spaced abutments, a circuit terminal contact on the block which normally extends midway between said abutments, said contacts being brought into engagement by the movement of said sash, thereby closing a circuit.

In testimony whereof I affix my signature in presence of two witnesses.

JOHN R. SANDBERG.
